UNITED STATES PATENT OFFICE.

ANTHON W. ELSTER, OF CANTON, SOUTH DAKOTA.

STRETCHER-BRACE.

1,273,048.

Specification of Letters Patent. Patented July 16, 1918.

Application filed July 12, 1917. Serial No. 180,195.

To all whom it may concern:

Be it known that I, ANTHON W. ELSTER, a citizen of the United States, residing at Canton, in the county of Lincoln and State 5 of South Dakota, have invented certain new and useful Improvements in Stretcher-Braces, of which the following is a specification.

This invention relates to new and useful 10 improvements in fence wire stretchers and the principal object of the invention is to provide means for stretching the wires beyond the corner post so that they may be nailed thereto.

Another object of the invention is to provide means whereby the wires while still in 15 stretched condition can be turned on the end post to start another stretch of fence so that the strain will not be thrown on the one set 20 of staples in the end post.

A further object of the invention is to provide means engaging with the end post for supporting the wire stretcher beyond the 25 post so that the wires are in stretched condition at the post and may be nailed thereto.

Another object of the invention is to provide a device of this character, which is 30 simple and durable in construction, reliable and efficient in operation and one which can 35 be manufactured and placed upon the market at a minimum cost.

The invention also consists in certain other 40 features of construction and in the combination and arrangement of the several parts, 45 to be hereinafter fully described, illustrated in the accompanying drawings and specifically pointed out in the appended claim.

In describing my invention in detail, reference will be had to the accompanying 50 drawings, wherein like characters denote like or corresponding parts throughout the several views, and in which:

Figure 1 shows the invention in use, the fence being shown from the rear side.

Fig. 2 is a plan view of Fig. 1.

In these figures 1 indicates the corner post 55 of the fence, 2 indicates an intermediate post while 3 represents the wires. 4 represents a cross head or stretcher bar to which the fence wires are connected in any suitable manner. 5 represents the stretcher, of any suitable form, which is connected with the bar 4 by the chain 6 and is operated by the handle 7.

My improvement consists of means for supporting said stretcher beyond the post

and these means comprise a truss composed of a pair of angle iron bars 8, whose leaves are drawn toward each other at their outer ends astride a plate 9 and pivoted thereto 60 in such a manner that said bars may be moved so that they are in contact with each other or that they may be swung apart so that they diverge from the plate, as shown in Fig. 1. At their free ends said bars are 65 provided with forks 10 of separate pieces of material riveted to the bars 8 and having their ends flattened and with the space between the forks curved to conform to the shape of the post, as shown in Fig. 2. A 70 chain 11, or other flexible connection connects the forked ends together so as to prevent the bars 8 from moving too far apart. If a chain is used I prefer to place a hook 12 thereon so that the same may be adjusted 75 as to its length. The upper end of the device has for each forked arm provided with a hole 13, one of which is to receive a rope or chain 14 which is to have its other end fastened to the post 2 so as to support the 80 device in position while the fence is being stretched. The plate 9 carries a hook 15 at its inner end to which the stretcher 5 is connected by means of the flexible connection 16. It will be seen that this hook is centrally 85 located in relation to the hinges of the bars 8 so that the stretcher is carried centrally of said bars. The outer end of plate 9 is provided with a double hook 17 to receive a rope or chain 18, the other end of which is to be 90 connected to a peg or the like. This chain 18 acts as a brace to prevent the device from swinging on the post while the wire is being stretched. By having the double hook 17 the bracing chain 18 may be placed on one 95 side or the other of the device, as desired, and the same is true of the rope 14 in connection with the holes 13.

In using the device the chain 11 is adjusted to suit the height of fence and then 100 the bars 8 are moved apart and their forked ends placed against the post, the rope or chain 14 being fastened to the post 2 to hold the device in position. The stretcher is then connected with the hook 15 and the stretcher 105 operated to stretch the fence. After the fence is sufficiently tight the wires are stapled to the post and then the device may be swung on the post to begin a new stretch of fence. Another set of staples may then be placed 110 in the post so as to relieve the strain off the first set when the stretcher is removed.

While I have shown and described the invention as applied to a corner post, it will be understood, that I do not wish to be limited to this use of the invention as it may be applied to one of the intermediate posts just as well.

It is thought from the foregoing that the advantages and novel features of my invention will be readily apparent.

10 I desire it to be understood that I may make slight changes in the construction and in the combination and arrangement of the several parts, provided that such changes fall within the scope of the appended claim.

15 I claim as my invention:

In a device of the class described, the combination with a cross head adapted to be attached to the fence wires, and a wire stretcher connected with said cross head; of

a trussed brace comprising a pair of arms of L-shaped cross section having forks in their outer ends adapted to be seated against a fence post and their leaves at their inner ends drawn toward each other, a plate pivoted between said leaves, a connection between its inner end and said stretcher, a double hook through its outer end, and a chain connected with one extremity of said hook and adapted to be led laterally from the truss and attached to a peg in the ground.

In testimony whereof I affix my signature in presence of two witnesses.

ANTHON W. ELSTER.
